UNITED STATES PATENT OFFICE.

JAMES ELLIS, OF LONDON, ENGLAND.

COLLAPSIBLE CRATE, BOX, AND THE LIKE.

1,374,993.

Specification of Letters Patent. Patented Apr. 19, 1921.

Application filed April 10, 1918. Serial No. 227,625.

To all whom it may concern:

Be it known that I, JAMES ELLIS, a subject of the King of Great Britain, residing in the county of London, England, have invented new and useful Improvements relating to Collapsible Crates, Boxes, and the like, of which the following is a specification.

This invention relates to collapsible crates, boxes and similar articles of transport and consists essentially of an improved construction of such devices whereby same are rendered capable of occupying little space in transit when empty and of ready erection when required for use as containers of articles. A further improvement consists in rendering a part of the device capable of forming a non-detachable hinged lid or cover.

According to this invention when applied to a crate the device comprises four rectangular frame-like parts each of which is composed of end pieces or bars joined by means of slats. Two of the rectangular parts are narrower than the other two and are adapted to fit within or between the end pieces or bars of the two wider parts to which they are joined by hinge pins the said pieces or bars being joined together by intermediate bars or slats applied either upon the inner or outer side thereof and having a capability of hinging at their points of connection. One pair of or two opposing hinge pins are made detachable and upon removing the same that end of the part is freed and the said part may be turned upon its remaining hinge pins so as to constitute a hinged lid or cover and when turned away from its freed joint permits of the admission of articles into the crate or receptacle.

In constructing a collapsible box on the same principle the end pieces are joined by boards of suitable area and detachable boards take the place of the intermediate bars the latter boards being attached by screws or other fixing means when the parts have been erected in position. One of the parts serves as a hinged lid or cover in a similar manner to that above described in connection with a crate.

In order that the invention may be readily understood and carried into effect I will proceed to describe the same more partic-

ularly with reference to the accompanying drawings in which:—

Fig. 1 is a perspective view of a crate constructed in accordance with the invention.

Fig. 2 is a view showing the crate collapsed.

Figs. 3 and 4 are respectively a side view and a plan illustrating the parts which constitute the improved receptacle same being shown in connection with a box like structure.

Fig. 5 is a side view showing the said parts erected to form a box.

Fig. 6 is a transverse section and

Fig. 7 a fragmentary longitudinal section on the line 7—7 of Fig. 6 of a construction of crate in which detachable end pieces are employed in place of the intermediate bars.

Fig. 8 is an end view of a modified construction of box.

Fig. 9 is a fragmentary view looking at 75 the right-hand side of Fig. 8.

Fig. 10 is a view illustrating the arrangement of the parts and indicating the mode of hinging and folding for transport when empty and for erecting.

Fig. 11 is an end view of the device collapsed.

Fig. 12 is a plan of a form of hinge suitable for employment in connection with the device.

Referring to Figs. 1 and 2 the four rectangular frames or parts are indicated by end pieces or bars 1—1, 2—2, 3—3, 4—4 which are joined by slats 5 so constituting the top, back, bottom and front of the crate.

The rectangular frames or parts 1—1, 3—3 are adapted to fit within or between the parts 2—2, 4—4 to which they are attached by hinge pins 6.

By making two of the hinge pins detachable say for instance those at the points *a* *a* the frame 1—1 with the slats 5 may be turned about the other two hinge pins (6) and be rendered capable of serving as a hinged lid or cover.

The frame parts 2—4 at opposite sides of the structure are joined by intermediate bars or slats 7 which are secured by pins 8 so as to be capable of hinging at their points of junction.

It will be apparent that as a result of the mode of connecting and hinging the parts the device is capable of being col-

lapsed so as to assume the flat or approximately flat condition indicated in Fig. 2 where it will be seen that the frame parts work together in a manner similar to the 5 parts of a parallel ruler. The construction therefore affords a device readily adapted for being collapsed (Fig. 2) and re-erected (Fig. 1). Upon removing the hinge pins at *a a* as hereinbefore described the part 10 1 so freed may be turned back thereby enabling the crate to be loaded or filled and to be afterward secured with ease and rapidity. Crates so constructed may be used again and again so that considerable economy 15 is effected in material and owing to the small space occupied when collapsed the cost incidental to returning a number of crates is not exorbitant.

In constructing a box on the principle 20 just described with reference to a crate the frame like parts 1—1, 2—2, 3—3, 4—4 instead of being joined by slats 5 as in Figs. 1 and 2 are joined by boards 9 Figs. 3 to 25 5 the parts 1—1 3—3 being provided with detachable boards 10 which serve to close the ends or sides of the box. The detachable boards are necessary in order to admit of collapsing the frame parts and the said boards are secured to the respective bars 30 pertaining to the parts by means of screws or other suitable fixing devices. The detachable parts 10 are shown separate from the frame bars 1—1 3—3 in Fig. 4 holes for the reception of screw pins or bolts being indicated at 11 (Figs. 3 and 4) and the screw pins or the like at 12 (Fig. 5). Upon removing the detachable boards 10 from the frame like bars 1—1 3—3 the parts 35 may be collapsed in a manner similar to that shown and described with reference to the crate (Fig. 2) with the exception as will be seen that the boards 10 are separate while the intermediate bars 7 remain integral with the frame parts. The arrangement 40 of detachable hinge pins as described in connection with the crate enables one of the frame parts to be deflected or turned so as to afford a hinged lid or cover whereby the box may be charged or filled with articles 45 or material as desired. Although the arrangement necessitates the employment of detachable boards for closing the sides of the frame parts the erection of the device is capable of expeditious accomplishment 50 and a firm and safe closure afforded with ample protection for articles inserted therein.

A crate when desired may be provided 60 with detachable ends Figs. 6 and 7 in place of the hinged intermediate bars 7. In that case the ends which may be formed of transverse bars 19 and longitudinal slats 20 are inserted so that both the bars 19 bear laterally against the end pieces or bars 2, 4 and 65 the lower bar 19 takes a bearing on the end

piece or bar 3. When the lid or cover is turned so as to close the crate the top bar 1 bears upon the upper transverse bar 19. Thus the structure is rendered stiff and firm.

According to the modified construction of the box form of device shown in Figs. 8 to 11 the detachable end pieces of boards 10 are provided with dowel pins 13 which take into holes formed for their reception 70 in the corresponding frame parts 3—3 or in the boards 15 which are secured to the said frame parts similar boards 14 being secured to the frame parts 2—2 and 4—4. In this construction the collapsibility is obtained by hinging the parts so that in end view they may be bent or folded as shown 80 in Fig. 10 and then the parts pressed closer together and superposed to assume the flat condition shown in Fig. 11 the detachable 85 end pieces or boards 10—10 being placed between the parts 1—1 2—2 and 3—3 4—4.

The frame parts are hinged for the most part in a manner similar to the previously described arrangements except that the 90 wider frame parts are those indicated by 1—1 3—3 and are shown as constituting the top and bottom frames of the receptacle. In order to obtain the collapsibility indicated in Fig. 11 the middle section or frame 95 parts are joined by hinges such as 16 composed of approximately L-shape plates having the pin or pivot 17 disposed inwardly away or remote from the adjacent outer or junction ends of the frame parts which carry 100 the plate portions of the hinge the arrangement admitting of the folding together of the parts so as to present the compact form shown in Fig. 11. The detachable boards 10 in addition to the dowel pins 13 are secured 105 in position by bolts 18 which are passed through the bars 2—2, 4—4 when the parts are erected to form the box. The lid portion say the frame parts 1—1, with the board 15 is secured by detachable pins or bolts as previously described. This mode of construction 110 may obviously be applied to a crate if desired.

In Fig. 10 the arrows *b b* indicate the direction of movement in order to collapse the 115 device the middle parts turning upon their hinges as will be readily seen on referring to the drawing. Having turned the outer parts upon their adjoining middle parts the whole device may be collapsed so as to assume the position shown in Fig. 11 the boards 10 being accommodated in the spaces between the said outer and middle parts. To erect the device so as to cause the same to 120 assume the form of a box the outer parts are turned in the direction indicated by the arrows *c c* the middle portions being opened out so as to assume a right-angle. Thus the frame part 1—1 with the boards 15 becomes say the top the part 2—2 with board 14 the 125 130

back the part 3—3 the bottom and the part 4—4 the front. The boards 10—10 are then placed in position to form the sides or ends of the box and secured as before described by means of the dowel pins 13 and bolts 18. A very firm and substantial structure is hereby obtained and owing to its collapsibility and portability is capable of service again and again a considerable economy being effected in material time and labor.

The hinge 16 is shown detached in Fig. 12 from which it will be seen that the construction comprises two approximately L-shape plates 21, 21 adapted for being secured to the desired frame parts by screws or other fixing means the hinge or pivot pin 17 being set away from the outer angles of the plates so as to permit of a longer heel or butt as regards the frame parts at the back of the hinge pin thereby enabling the frame parts to readily assume the various attitudes necessary in erecting or collapsing the device.

It will thus be seen that when the device is compactly folded or collapsed the formation of the plates constituting the parts of the hinge 16 is such as to enable the panels or boards 14, 15 to be snugly accommodated

between the bars of the frame parts to which the hinge plates are secured.

What I claim is:—

In a collapsible crate the combination of a frame comprising four rectangular parts forming top, bottom and side portions the top being adapted to serve as a lid or cover for the crate, each rectangular part being formed of two spaced bars connected by slats the extremities of the bars of the top and bottom portions fitting between the extremities of the bars of the side portions; hinges for connecting said portions to each other whereby said portions may be laid in a flat condition or folded upon each other one pair of said hinges being detachable; and detachable end parts formed of spaced bars connected by slats said bars bearing laterally against the bars of the side portions, the lower bars of said end parts bearing on the bars of the bottom portion while the upper bars of said end parts serve as rests for the bars of the top or lid portion when said top or lid portion is in the closed position, the end parts being detachably secured to said frame.

JAMES ELLIS.
